UNITED STATES PATENT OFFICE.

GEORGE DAVIS, OF NEW YORK, N. Y.

DESIGN FOR A SHOE.

No. 39,919.

Specification for Design.

Patented April 13, 1909.

Application filed November 9, 1908. Serial No. 461,829. Term of patent 3½ years.

To all whom it may concern:

Be it known that I, GEORGE DAVIS, a subject of the King of Britain, and a resident of New York, borough of Brooklyn, county of Kings, and State of New York, have invented a new and original and ornamental Design for Shoes, of which the following is a specification, reference being had to the accompanying drawing, forming part thereof, and in which the figure shows a side elevation of a shoe having my improved design as applied thereto.

My new design consists of a configuration and ornamentation composed of a border on the upper of a shoe which consists of a plural-

ity of squares arranged in sets of five, the different sets being spaced apart so as to make a pleasing appearance. The border on which the squares are arranged is slightly raised and the squares are raised slightly above the border, and this raised feature adds greatly to the pleasing effect produced by the design.

I claim—

The ornamental design for a shoe as shown and described.

GEORGE DAVIS.
